UNITED STATES PATENT OFFICE.

RUDOLF MARSCHALL, OF VIENNA, AUSTRIA-HUNGARY.

DESIGN FOR A MEDAL.

No. 40,004.

Specification for Design.

Patented May 25, 1909.

Application filed April 25, 1908. Serial No. 429,288. Term of patent 7 years.

To all whom it may concern:

Be it known that I, RUDOLF MARSCHALL, a subject of the Emperor of Austria-Hungary, residing at IV Starhemberggasse 40, Vienna, Austria-Hungary, have invented a new, original, and ornamental Design for a Medal, of which the following is a specification, reference being had to the accompanying drawing, forming part thereof.

Fig. 2 a plan view of the reverse side of a medal, showing my new design.

I claim:

The ornamental design for a medal, as shown.

RUDOLF MARSCHALL.
